US00D945826S

(12) **United States Design Patent** (10) **Patent No.:** **US D945,826 S**
(45) **Date of Patent:** ** *Mar. 15, 2022

- (54) **REUSABLE SEALABLE CUP**
- (71) Applicant: **ZIP TOP, LLC**, Austin, TX (US)
- (72) Inventors: **Rebecca M. Finell**, Austin, TX (US); **Joshua J. Nelson**, Mesa, AZ (US)
- (73) Assignee: **ZIP TOP, LLC**, Austin, TX (US)
- (*) Notice: This patent is subject to a terminal disclaimer.
- (**) Term: **15 Years**
- (21) Appl. No.: **29/699,320**
- (22) Filed: **Jul. 24, 2019**

Related U.S. Application Data

- (63) Continuation-in-part of application No. 29/618,106, filed on Sep. 19, 2017, now Pat. No. Des. 876,891.
- (51) **LOC (13) Cl.** **07-01**
- (52) **U.S. Cl.**
USPC **D7/509; D7/523; D9/707**
